HANS H. WANDERS, OF BROOKLINE, MASSACHUSETTS.

METAL-WORKING MACHINE.

1,373,690.

Specification of Letters Patent.

Patented Apr. 5, 1921.

Application filed February 7, 1918. Serial No. 215,896.

To all whom it may concern:

Be it known that I, HANS H. WANDERS, a subject of the German Emperor, residing at Brookline, in the county of Norfolk and 5 State of Massachusetts, have invented new and useful Improvements in Metal-Working Machines, of which the following is a specification.

The object of this invention is to provide a 10 metal-working machine which may be employed for operating simultaneously upon different portions of the work which are eccentric in respect of each other. For example, in the production of crank shafts, 15 it is desirable to turn or to finish accurately the cranks, which are arranged out of alignment with the axis of the shaft, and the specific object of my present invention is to provide a machine by which all of the various cranks may be accurately turned or finished simultaneously. As a feature of the 20 invention, the member to be acted on will preferably be held in a relatively fixed non-rotatable position while the tool members 25 will have both circumferential and axial rotation relative to the member to be acted on.

In the illustrated embodiment of the invention, I accomplish these objects by the employment of a plurality of rotary annular 30 tool carriers which are arranged to rotate about different axes and which carry tools for operation upon the cranks of a crank shaft held against rotation by the work hold- 35 ers or carriers.

On the accompanying drawings,—

Figure 1 represents in side elevation a machine embodying the invention.

Fig. 2 represents an end elevation of the same.

Fig. 3 represents a section on the line 3—3 of Fig. 1, looking in the direction of the arrow.

Fig. 4 represents in detail the steady rests and centering jaws for the crank shafts.

Fig. 5 represents one of the rotary tool carriers and its bearing frame.

Fig. 6 represents a side elevation of the same.

Fig. 7 represents a section on the line 7—7 50 of Fig. 5 on a larger scale.

Fig. 8 represents a section on the line 8—8 of Fig. 5, on a larger scale.

Fig. 9 represents a section on the line 9—9 of Fig. 5.

Fig. 10 shows the face of one of the mill-

ing cutters which is utilized in the present embodiment of the invention.

Fig. 11 represents in plan view a portion of the power-transmitting mechanism which is employed for transmitting power from 60 the main shaft to the various tool carriers.

Fig. 12 is a more or less diagrammatic view showing the mechanism for transmitting power from the main driving shaft to 65 the shafts by which the tool carriers are rotated, and the cutters themselves are rotated about their several axes.

Fig. 13 illustrates the arrangement of the 70 annular tool carriers for reducing the cranks of a four-throw crank shaft.

Fig. 14 shows the arrangement of the cutter carriers for a six-throw crank shaft.

Of course it will be understood that the invention is capable of a variety of embodiments, and that, while I have illustrated the 75 same in the form of a machine for reducing the cranks or crank pins of a crank shaft, it is capable of application for many purposes. I also desire to have it understood that the machine is illustrated more or less 80 conventionally but in sufficient detail to make clear the principle of its operation; and further that the phraseology which I employ herein is for the purpose of description and not of limitation.

As illustrated, the machine is provided with a bed 20 which is illustrated as being of the cabinet type, and upon one part of which are supported the bearing frames for the annular tool carriers and upon another 90 part of which is supported a movable carriage in which one end of the work may be clamped. The bed is provided with a table 21, and at a higher elevation with a second table 22. Upon the table 21 of the bed is 95 adjustably bolted or otherwise secured a tail stock 23 provided with a split tubular clamp 24 in which there is slidably mounted a dead spindle 25. The clamp is closed by a handle nut 26 on a screw (not shown) carried by the stationary portion of the clamp. By loosening the bolts or other fastenings, the stock 23 may be adjusted to different positions lengthwise of the bed. The spindle 25 is ordinarily held against rotation, and it 100 carries on its inner end a chuck 27 in which one end of the crank shaft to be operated upon is secured. Any suitable form of chuck may be utilized such as the one which I shall describe in connection with the head stock 110

for holding the other end of the crank shaft. Upon the table 22 there is gibbed a sliding head-stock carriage 28, the apron 29 of which supports a shaft 30. This shaft at 5 its front end is equipped with a hand wheel 31 by which it may be rotated, and at its other end with a gear 32 meshing with a stationary rack 33 on the side of the bed. By rotating the hand wheel 31, the carriage 10 28 may be moved lengthwise of the bed in one direction or the other. To limit the movement of the carriage on its guideway in either direction, stops 34, 35 are located at the ends of the guideway and 15 project into the path of movement of the carriage. After the carriage has been adjusted to proper position, it may be locked against movement by a clamp which comprises a gib 36, a screw projecting upwardly 20 therefrom through the front portion of the base of the carriage, and a handle nut 37 bearing against the upper face of the base. By tightening the nut, the carriage may, after adjustment, be held securely against 25 longitudinal movement. The carriage is provided with a stock 38, which is shown as in the form of a tubular split clamp which may be tightened upon a hollow spindle or sleeve 40 by a locking nut 39. At its outer 30 end the sleeve or spindle is provided with a collar 41 and at its inner end with a segment 42 which may constitute a portion of a chuck. The chuck also comprises a hinged clamping member 43 which is operated 35 by a nut 44 on a bolt 45 hinged at 46 to the segment 42. The chuck or clamping mechanism thus described grasps and securely holds the end of the crank shaft opposite that held by the chuck 27 on the dead 40 spindle 25. The sleeve or spindle 40 may be rotatively adjusted to rotate the crank shaft bodily about its axis for the purpose of positioning it in reference to the rotary cutter carriers. To this end, the segment 42 45 is provided with worm teeth 47 which intermesh with a worm 48 on a cross shaft 49 journaled in the carriage 38, and having on the front end thereof a hand wheel 50 by which it may be rotated. Sometimes it is 50 desirable to limit the rotation of the chuck and the crank shaft clamped thereby for the purpose of accurately positioning the cranks on the shaft in reference to the associated cutter carriers, and to this end the 55 stock 38 may be provided with two stops 51, 52, for engagement by the end of the segment 42. As illustrated in Fig. 3, these stops are located to permit the rotation of the chuck and the crank shaft through an 60 arc of 90° . The segment has on its face two lugs 142 and 143, one carrying an abutment 144 and the other a screw 145 between which the end crank arm or cheek of the crank shaft may be rigidly clamped. 65 From the description thus far given, it

will be seen that the ends of the crank shaft, which constitute its journals, may be rigidly clamped in the chucks of the two stocks which by analogy may be termed respectively the tail-stock 24 and the head-stock 38. By arranging the head-stock so that it may be fed lengthwise of the bed and by providing the tail-stock with the elongated spindle 25, it is possible first to clamp the ends of the crank shaft to be operated upon in the two chucks at a time when the carriage has been fed to the limit of its movement toward the right, and then bodily to feed the crank shaft to the left in position to locate the cranks accurately in 75 respect of the rotatable cutter carriers. Similarly, when the work upon the crank shaft has been completed, after unclamping the spindle 25, the head-stock may be fed to the right so as to remove the crank 80 shaft to a position where it may be disengaged from the chucks and taken out of the machine. After the crank shaft has been moved into position to permit the operation of the cutters thereon, the spindle 85 25 is clamped against rotative movement and the sleeve 38 is likewise clamped. In this connection, it may be observed that, after the crank shaft has been moved to position within the annular tool carriers, it 90 may be bodily rotated about the axis of its journals to bring the cranks in proper relation to the several cutters to permit the latter to operate thereon, and it is for this purpose that the head-stock is provided with 95 the oscillatory or rotative sleeve and the worm mechanism for effecting its movement about its axis. In Fig. 1, the head-stock, indicated as being broken off at the right 100 end of the machine, shows the position 105 which the head-stock assumes after it has been moved to the right to withdraw the crank shaft from the cutter carriers.

The number of the cutter carriers and the bearing frames in which they are 110 respectively mounted depends upon the number of cranks on the crank shaft. When a shaft is provided with four cranks, there are preferably four cutter carriers, and likewise, if there are six cranks, six cutter 115 carriers are preferably provided. These cutter carriers are arranged to rotate about axes coincident with the axes of the cranks, the carriers and their frames usually being arranged in pairs, as regards their rotating 120 about the same axis. This arrangement in pairs is true only of a crank shaft, for in turning other kinds of work it is quite apparent that the axes of rotation of the cutter-carrying heads may all be parallel to 125 each other and no two of them be in alignment or coincident. In the machine illustrated upon the drawing in Figs. 1 to 13 inclusive, there are sufficient cutter carriers to operate simultaneously upon the four 130

cranks of a four-throw crank shaft. Each carrier is mounted in a suitable bearing frame supported upon the table 21 of the bed, but these frames are removable and 5 are interchangeable with others, so that the machine can quickly be adapted for operating upon crank shafts of different sizes or having different numbers of cranks. As illustrated, there are four frames each of 10 which is indicated as a whole at 54. The base of each frame is secured to a slide or block 55 which extends across the table 21 and is provided with gibs 56, 56, engaging ribs 57 on the front and rear of the bed. 15 Any suitable means may be utilized for clamping the gibs against the ribs to prevent dislocation of the blocks and the frames carried thereby. The blocks vary in thickness, so that, by removing one block and 20 substituting another of greater or less thickness, the whole frame may be raised or lowered to locate its axis in the desired horizontal plane. Preferably each block is provided with a plurality of threaded socket- 25 sets for screws 59, passed through slots in the base of the associated frame, so that the frames are capable of lateral adjustment in respect to the bed and may be secured after such adjustment. By properly locating the 30 threaded sockets for the screws 59, the heads may be adjusted so as to lie at an angle other than 90° to the longitudinal lines of the bed, so that the axes of rotation of the cutter carriers themselves may 35 be inclined in respect to the axis of the two chucks. The blocks 55 and the frames thereon may be adjusted longitudinally of the bed 21 and secured in place after adjustment.

40 Mounted to rotate in each frame, there is a tool carrier, the details of construction of which are illustrated on sheet 2 of the drawings. This cutter carrier consists of a ring or annulus 60, the rim portion of which is 45 journaled in a bearing afforded by the frame, as shown in Fig. 8. The frame 54 is provided with a flange 162, between which and a cover 61 bolted to the frame, the rotatable carrier is held against axial movement. The 50 annular carrier is provided with three bearing surfaces, one its peripheral surface as indicated at 62, one a flat surface 63 on one face, and the other a beveled surface 164 on its other face. This rotatable carrier may 55 be provided with reentrant cutters or tools of any suitable character for operating upon the work. For example, it may be provided with forming cutters, with a milling head, or with a grinding tool. I have illustrated, 60 however, each carrier as being provided with a milling cutter which is arranged radially of the head and rotated about its axis during the rotation of the head. The carrier is provided with a ribbed projection 64 which 65 extends radially inwardly and which is utilized in supporting a tool close to the work. In the present case, this projection is formed with a socket to receive the milling spindle and its adjuncts, the socket being indicated at 65. Into the socket is inserted a short 70 sleeve 66 in which the reduced end of the spindle 67 is inserted, and a longer sleeve 68 in which the other end of the spindle is mounted. The sleeve 68 is illustrated as being provided with an external thread for 75 engaging a complementary thread in the socket 65. To hold the cutter spindle 67 against axial movement, it is threaded as at 69 to receive the two collars 70, 71. Between the collar 71 and the end of the sleeve 68 80 there is a washer 72. The outer end of the sleeve 68 is cupped to receive an anti-friction bearing comprising the two races 73, 74, and the balls 75. The race 73 abuts against the bottom of the socket, while against the 85 race 74 bears a shoulder 76 formed on the spindle 67. The whole sleeve 68 may be rotated to adjust the spindle lengthwise or axially, and the collars 70, 71 may be adjusted to compensate for wear. By the construction described, the spindle is held 90 against axial movement. To hold the sleeve 68 after it has been adjusted, the projection 64, which is approximately tubular with longitudinal ribs, is split as shown in Fig. 7 95 and is provided with a clamping screw 77 to draw the split portions together and tightly clamp the sleeve 68. Upon the projecting end of the spindle 67 there may be secured any suitable form of milling cutter. 100 As shown, the end of the spindle is tapered as at 78 to fit a complementary socket in the milling head 79. This head is secured to the spindle by a screw collar 80, and is held 105 against rotation relatively to the spindle by a cross pin 81 which fits in internal grooves or slots in the head 79. The face of the head is provided with a number of blades or cutters as shown in Fig. 10. With convenience, four of the blades 82 may be relatively 110 long and arranged with one face of each in a plane radial to the axis of the spindle. The other blades 83 may be relatively short, as shown, and may be located only in the outer portions of the face of the head. As previously stated, instead of employing a milling cutter, the end of the spindle could be equipped with any other form of tool such as a grinding wheel, or the spindle itself 115 could be provided with a turning or forming cutter, in which event of course the spindle would be held against rotation. In the present instance, however, inasmuch as I have illustrated a milling cutter, I have also shown means by which its spindle may be 120 rotated about its axis, but I will defer the explanation of this mechanism until I have described the means by which each annular cutter carrier may be rotated.

125 Each annular cutter carrier is provided 130

with worm teeth 182, formed on its periphery as illustrated in Figs. 5, 8 and 9, and a worm 183 meshes therewith. This worm 183 is formed on or secured to a shaft 84 which 5 extends into the bearing frame in which the tool carrier head is mounted and is journaled in suitable bearings provided therefor. The shaft projects rearwardly beyond the frame and is provided with means by which power 10 may be transmitted thereto to effect its rotation. Any suitable means may be employed for driving the shafts 84 to cause the rotation of the several tool carriers. In Figs. 2, 11 and 12, I have shown one form 15 of power-transmitting mechanism which will serve the purpose. This mechanism comprises a main drive shaft 86, which, through reducing gears 87, 88, 89 and 90, drives a shaft 91 parallel to that at 86. From the 20 shaft 91 power is transmitted to the worm shafts 84, by any suitable mechanism. As shown, the shaft 91 is provided with sprocket wheels 93 for driving two chains 92, 92, each of which engages the sprocket wheels 25 85 of two of the shafts 84. Consequently, when the shaft 91 is in rotation, all four of the worm shafts 84 are rotated simultaneously.

The several milling cutters, which are 30 supported by the annular cutter carriers, are rotated about their respective axes by mechanism which will now be described. Each spindle 67 has splined thereon a bevel gear 100 (see Fig. 8), the teeth of which intermesh with bevel gear teeth formed on annular gear 101 which is journaled in the head and held in place by an annulus 102. The hub of the gear 100 bears against suitable anti-friction thrust bearings indicated 35 40 as a whole at 103, there being a washer at 104 at the other end of the gear. The worm gear 101 is engaged with a worm 105 formed on or secured to a shaft 106 which is journaled in the associated frame. One end of the shaft projects beyond the rear of the frame, as shown in Fig. 5, and is provided 45 with means by which rotation may be imparted thereto. As illustrated, each of the worm shafts 106 is provided with a sprocket 50 107 for engagement with sprocket chains 108 driven by sprockets 109 on the main driving shaft 86.

From the explanation thus far given, it 55 will be quite apparent that, when the worm shafts 106 are rotated, the worm gears 101 likewise will be rotated and will in turn, by reason of their intermeshing relation with the gears 100, effect the rotation of the cutter spindles at a relatively high speed. 60 Where a four-throw crank shaft is to have its cranks reduced, the bearing frames for the tool carriers may be located in the relative position shown in Fig. 13. Two of the frames, to wit, the two middle frames, are 65 located at a slightly higher elevation than

the two outer frames, so that the axes of the milling cutters carried thereby will not intersect the axis of the crank upon which the cutter is to operate. This, however, is merely incident to the employment of mill- 70 ing cutters, as the frames may be adjusted to any desired height by employing blocks 55 of different heights. Where a six-throw crank shaft is to be treated, the frames may be relatively located as illustrated in Fig. 14. 75

The machine is preferably provided, at points between the two stocks 23 and 38, with means for resisting the thrust of the cutters upon the cranks and for centering the crank shaft. Any suitable means for 80 accomplishing this result may be employed, but in Fig. 4 I have shown a device or appliance which will accomplish the purpose. Referring to Fig. 4, I employ two floating steady rests or V-blocks 110, 110, which are 85 supported by the two angle arms 111, 111. As a matter of incidental construction, the blocks 110 are attached to screws 112 which pass loosely through apertures in the angle arms and which are encircled by springs 113 90 introduced in sockets in said arms and bearing against the ends of the sockets and the blocks 110. The two angle arms are respectively pivoted at 114 to a cross bar or carrier 115 which is gibbed to the table 21 of 95 the bed by gibs 116 which engage the ribs 57, 57. The two angle arms may be drawn together by a long eye-bolt 117 hinged by the pintle 118 to the upper end of the rear angle arm, and an elongated internally 100 threaded sleeve nut 119 provided at its end with a handle wheel 120. The inner end of the sleeve 119 bears against a member or block 121 which has a hook 122 engaging a groove 123 in the upper end of the forward 105 angle arm 111. By rotating the hand wheel 120, the angle arms may be drawn together or separated as desired. When they are separated, they may be held upright, or the front angle bar drawn forward by a handle 110 bar 124 which is secured to said front angle arm and projects forwardly toward the front of the machine.

The main drive shaft 86 may have power 115 imparted thereto from any suitable source. As shown, this shaft, the shaft 91, and the shaft 128 which supports the intermediate gears 88 and 89, are all mounted upon a bracket 129 which is affixed to the rear wall 120 of the bed as indicated in Figs. 2 and 11. The shaft 86 is provided with a large pulley 130 by which it may be rotated through a clutch introduced between it and the shaft. I have not shown this clutch mechanism, but I have indicated at 1300 a lever located at 125 the front of the machine by which this clutch may be controlled. I have also indicated at 131 another clutch lever for controlling the clutch for the sprockets 93 on the shaft 91.

After the bearing frames for the cutter carriers have been located upon the table 21 of the bed in their proper positions, they may be all tied together by a longitudinal 5 bar 133 to insure a rigid construction and prevent the upper portions of the frames from spreading or from yielding in one direction or the other. This bar 133 may be formed in any suitable way and may be 10 secured by any convenient means to the frames.

The operation of the machine is as follows: Assuming that the head-stock 38 has been moved to the right as far as it will go, 15 and the spindle 25 has been projected to the right through the interior of the annular cutter carriers, a crank shaft, on which the cranks are to be reduced, is clamped in the two chucks carried by the two stocks. The 20 hand wheel 31 is then rotated to carry the head-stock, the tail-stock spindle and the crank shaft to the left so as to bring the cranks in the vertical planes of the respective tool carriers, and thus bring the cranks 25 into potential working position in respect of the several cutters. In the case of a four-throw crank, the shaft is introduced with the cranks in the position indicated by dotted lines in Fig. 13. The steady rests are 30 then brought into operative position to engage one of the main journals between the ends of the crank shaft, and cause the V-blocks loosely to engage the journal. The head-stock is now clamped rigidly by operating the handle nut 37. By rotating the hand wheel 50, the sleeve 40 of the head-stock 38, and the crank shaft are indexed to 35 rotate the crank shaft bodily about its axis and bring the cranks thereof in position to be engaged by the milling cutters as indicated in full lines in Fig. 13. Before indexing the crank shaft, it is desirable to start the milling cutters in operation, and this, of course, will be done by the manipulation 40 of the lever 1300 which controls the clutch for the shaft 86. As soon as the indexing of the crank shaft is completed, the clamp nuts 26 and 39 are set to hold the crank shaft 45 against further rotation, and the steady rests are adjusted into firm engagement with the journal of the crank shaft. Then the cutter carriers are set in rotation by a manipulation of the lever 131 which controls the clutch for the sprockets 93 on the shaft 91. 50 As the cutter carriers are rotated about the axes of the several crank pins, the milling cutters continue their rotation and the crank pins on the crank shaft are reduced and finished. The crank shaft is removed from 55 the machine, after the operation is completed, by loosening the clamp nuts 26 and 39 and moving the head-stock to the right, before which it is necessary to stop the rotation of the cutter-carrying heads and to release the steady rests and usually to stop 60 65

the rotation of the milling cutters. The crank shaft, of course, is reversely indexed to bring it to a position where it is disengaged from the cutters.

Having thus explained the nature of my 70 said invention and described a way of making and using the same, although without attempting to set forth all of the forms in which it may be made or all of the modes of its use, what I claim is:

1. A metal-working machine comprising an annular tool carrier, a bearing therefor, work holders adapted to hold work extending through said carrier, means by which said work may be fed longitudinally into 80 and out of position within said tool carrier, mechanism for rotatively indexing said work, and means for rotating said annular tool carrier.

2. A metal-working machine comprising 85 means for supporting a crank shaft and holding it against rotation, cutting mechanisms arranged to operate simultaneously on a plurality of the crank pins of said crank shaft, and mechanism for effecting the simultaneous operation of said cutting mechanism.

3. A metal-working machine comprising means for supporting a crank shaft and holding it against rotation, a plurality of 95 95 annular tool carriers encircling said crank shaft and concentric with the crank pins thereof when the latter are in position to be operated on, and means for simultaneously rotating said tool carriers.

4. A machine for simultaneously reducing a plurality of the crank pins of a crank shaft, comprising holders having rotatable chucks for engaging the end journals of said shaft, annular tool carriers adapted to encircle the several crank pins of said shaft and having tools for operating on said crank pins, mechanism for rotating one of said chucks to index the crank shaft, and mechanism for causing a relative rotation of said 105 110 crank shaft and all of said tool carriers simultaneously.

5. A machine for reducing the crank pins of a crank shaft, comprising holders for engaging the end journals of said shaft, annular tool carriers adapted to encircle the several crank pins of said shaft and having tools for operating on said crank pins, a main shaft, and mechanism, actuated thereby for rotating said tool carriers simultaneously about their respective axes.

6. A metal-working machine comprising a plurality of approximately parallel annular tool carriers arranged to rotate about non-alined axes and having reentrant tools to 125 engage work passing through said carriers, and mechanism for simultaneously rotating said tool carriers.

7. A metal-working machine comprising a plurality of approximately parallel annular 130

tool carriers arranged out of axial alinement, means for feeding the work into the interior of said annular carriers, and mechanism for simultaneously rotating said tool carriers about their respective axes and about the work.

8. A metal-working machine comprising a plurality of approximately parallel annular tool carriers, a bed, bearings on said bed in which said carriers are mounted, work holders normally located beyond the opposite ends of the plurality of cutter carriers, for supporting work passing through the carriers, and mechanism for simultaneously rotating said tool carriers about the work.

9. A metal-working machine comprising a bed, holding means on said bed for supporting the work, an annular tool carrier arranged to encircle the work held by the work-holding means and being eccentric in respect of the axis of the work-holding means, a tool mounted on said carrier, means for rotating said tool carrier, means by which said work may be bodily indexed about its axis to bring a portion thereof in position to be engaged by the tool, and means for holding said work against rotation.

10. A metal-working machine comprising a bed, holding means on said bed for supporting the work, an annular tool carrier arranged to encircle the work held by the work-holding means and being eccentric in respect of the axis of the work holding means, a tool mounted on said carrier, means for rotating said tool carrier, mechanism for rotatively indexing said work about its axis to bring a portion thereof in position to be engaged by the tool, means for holding said work against rotation, and mechanism for moving said work-holding means to introduce the work longitudinally into and to withdraw it from said annular tool carrier.

11. A machine for reducing the crank pins of a crank shaft, comprising holders for engaging the end journals of said shaft, annular tool carriers adapted to encircle the several crank pins of said shaft, rotary tools carried by and projecting inwardly from the several annular carriers, and mechanisms for rotating the tool carriers and the tools simultaneously about their respective axes of rotation.

12. A machine for reducing the crank pins of a crank shaft, comprising holders for engaging the end journals of said shaft, annular tool carriers adapted to encircle the several crank pins of said shaft, rotary tools carried by and projecting inwardly from the several annular carriers, mechanism for rotating the several carriers, and independently controlled mechanism for rotating the several tools about their axes of rotation while said carriers are in rotation.

13. A metal-working machine comprising a bed, a tail-stock thereon having an elongated

slidable rotatable spindle, a chuck on said spindle, a head-stock having a rotatable spindle provided with a chuck, an annular tool carrier arranged between said chucks to permit the work to pass therethrough, means for sliding said head-stock toward and from the tail-stock, and means for clamping said spindles against rotation.

14. A metal-working machine comprising a bed, a tail-stock thereon having an elongated slidable spindle, a chuck on said spindle, a head-stock having a spindle provided with a chuck, an annular tool carrier arranged between said chucks, means for moving said head-stock and said tail-stock 75 spindle (when the chuck thereon is clamped to the work) in a direction longitudinal of the work, and means for clamping said spindles to their respective stocks to hold the work against rotation.

15. A metal-working machine comprising a bed, a tail-stock thereon having an elongated slidable spindle, a chuck on said spindle, a head-stock having a spindle provided with a chuck, an annular tool carrier arranged 90 between said chucks to permit the work to pass therethrough, mechanism for rotating said tool carrier about the work, means for moving said head-stock and said tail-stock 95 spindle (when the chuck thereon is clamped to the work) in a direction longitudinal of the work, means for indexing one of said spindles to rotatively adjust the work, and means for holding said spindles against rotation when the tool carrier is in operation.

16. A metal-working machine comprising a bed, a tail-stock thereon having an elongated slidable spindle, a chuck on said spindle, a head-stock having a spindle provided with a chuck, an annular tool carrier 105 arranged between said chucks to rotate about the work, mechanism for rotating the annular tool carrier, means for moving said head-stock and said tail-stock spindle (when the chuck thereon is clamped to the work) 110 in a direction longitudinal of the work, and means by which said spindles may be held against rotation.

17. A metal-working machine comprising a bed, a tail-stock thereon having an elongated slidable spindle, a chuck on said spindle, a head-stock having a spindle provided with a chuck, an annular tool carrier arranged between said chucks to receive the work therethrough, means for moving said head-stock and said tail-stock spindle (when the chuck thereon is clamped to the work) 120 in a direction longitudinal of the work, means for rotatively indexing one of said spindles to rotatively adjust the work, and 125 means by which said spindles may be clamped against rotation.

18. A metal-working machine comprising a bed, means thereon for holding a bar or shaft against rotation, a plurality of annu- 130

- lar tool carriers each adapted to encircle said bar or shaft and to rotate thereabout, a reëntrant tool on each carrier, a bearing frame for each carrier, and interchangeable slides of different thicknesses on the bed on which said frames are adjustably secured. 5
19. A metal-working machine comprising work holders for holding the ends of a bar or shaft to be operated on, a plurality of annular tool carriers adapted to encircle said bar, means for rotating said tool carriers, and work-steadying means arranged between said work holders. 10
20. A metal-working machine comprising a work holder for stationarily supporting the work, an annular carrier arranged to encircle the work, a tool spindle journaled in said carrier and having a tool thereon, gear teeth formed on or secured to said annular carrier, a gear on said spindle, an annular gear supported by the annular carrier and having gear teeth engaging the gear on the spindle, and independent worms engaging the toothed tool carrier and said annular gear for driving them independently of each other. 20
21. A machine for reducing the relatively eccentric crank pins of a crank shaft comprising work holders for engaging the end journals of said crank shaft and holding said shaft against rotation, a plurality of annular tool carriers encircling the several crank pins of said shaft and having reëntrant tools for operating on said crank pins, and mechanism for actuating said tool carriers simultaneously to cause the tools thereof to operate simultaneously upon said several pins. 30
22. A machine for reducing the crank pins of a crank shaft comprising work holders for engaging the end journals of said crank shaft, a plurality of annular tool carriers encircling the several crank pins of said shaft and having reëntrant tools for operating on said crank pins, mechanism for actuating said tool carriers simultaneously to cause the tools thereof to operate simultaneously upon said several pins, and steady-rest mechanism for engaging an intermediate journal of said crank shaft. 40
23. A machine for reducing the crank pins of a crank shaft comprising work holders for engaging the end journals of said crank shaft, a plurality of annular tool carriers encircling the several crank pins of said shaft and having reëntrant tools for operating on said crank pins, mechanism for actuating said tool carriers simultaneously to cause the tools thereof to operate simultaneously upon said several pins, and means for moving said crank shaft bodily about its axis to move said crank pins toward and from said tools. 50
24. A machine for reducing the crank pins of a crank shaft comprising work holders for engaging the end journals of said crank shaft, a plurality of annular tool carriers encircling the several crank pins of said shaft and having reëntrant tools for operating on said crank pins, mechanism for actuating said tool carriers simultaneously to cause the tools thereof to operate simultaneously upon said several pins, and means for moving said work holders to introduce said shaft into and to withdraw it from said annular tool carriers, including a work-holding spindle having a chuck movable longitudinally through all of said carriers. 65
25. In a metal-working machine of the character described, an annular tool carrier, having a reëntrant socketed projection located between the ends of said carrier, and a tool mounted in the socket in said projection. 70
26. In a metal-working machine, a bed, a tool carrier, and work-holding means comprising a sliding carriage, a spindle journaled thereon and having a worm gear thereon, a worm journaled in the carriage and intermeshing with said gear to index the spindle, a chuck carried by said spindle, and means for clamping said spindle against rotation. 80
27. In a metal-working machine, a bed, a tool carrier, a work holder, and steady-rest mechanism comprising a carrier on the bed, a pair of arms each of which is pivoted at its lower end to the said carrier, said pivoted ends being spaced apart, means for drawing together and separating the free ends of said arms, and steady rests supported by said arms between the ends thereof for engaging the work. 85
28. In a metal-working machine, a bed, a tool carrier, a work holder, and steady-rest mechanism comprising pivoted arms, means for drawing together and separating said arms, and steady rests supported by said arms for engaging the work, each rest being spring-tensioned and capable of limited movement relatively to its supporting arm. 95
29. In a metal-working machine, a bed, a tool carrier, a work holder, a steady-rest mechanism comprising pivoted arms, an eyebolt and handle nut for drawing together and separating the free ends of said arms, a slide on the bed to which said arms are pivoted, the pivots for said arms being spaced apart and the lower portions of said arms being divergent, and steady rests supported by the respective arms. 105

In testimony whereof I have affixed my signature.

HANS H. WANDERS.
